ALFRED R. ANTHONY, OF NEW YORK, N. Y., ASSIGNEE TO THE ANTHONY COMPANY,
OF NEW YORK, N. Y., A CORPORATION OF NEW YORK.

COMBINED OIL AND GAS BURNER.

1,022,649.

Specification of Letters Patent.

Patented Apr. 9, 1912.

Application filed June 1, 1910. Serial No. 564,376.

To all whom it may concern:

Be it known that I, ALFRED R. ANTHONY, a citizen of the United States, and resident of New York, in the county and State of New York, have invented certain new and useful Improvements in Combined Oil and Gas Burners, of which the following is a specification.

The present invention relates to improvements in burners which are adapted to burn a mixture of atomized hydrocarbon and air or a suitable gas mixed with air, and the object of the invention is to provide a burner of this type or class which shall consist of a minimum number of parts, and by which, in case it is employed for burning gas, a more intimate and thorough mixing of the gas and air prior to discharging the same through the outlet or combustion orifice of the burner will be effected than has been accomplished with the constructions herefore proposed or employed.

In the drawing,—Figure 1 is a longitudinal sectional view through a burner constructed in accordance with the present invention; Fig. 2 is a transverse sectional view on the line 2—2 of Fig. 1; Fig. 3 is a sectional view substantially on the line 3—3 of Fig. 1.

Referring to the drawings, it will be seen that the improved burner includes a casing composed of a body section A preferably made substantially circular in cross-section, having one end entirely open, and provided adjacent its other end with a lateral branch B constituting an air inlet. The open end of the body section A of the main casing is inclosed by a cap C which is adjustably connected with the section A by a suitable thread D so that the cap may be moved longitudinally of the body of the casing. The interior of the cap C which forms a continuation of the chamber provided by the section A is of greater diameter or cross sectional area than the interior of the body of the casing, and in its outer end said cap is provided with a centrally arranged outlet or combustion opening E.

Fitted within and extending through an opening formed in the end wall F of the casing opposite said adjustable cap is a

fitting preferably made as a casting in which are formed two concentric ducts or conduits G, H, the portions of which outside of the casing extend in opposite directions and are adapted to be respectively connected with suitable oil and gas supply pipes, I, K. Said fitting or casting may be secured in the opening in the end wall of the casing by any suitable means, a set screw L being shown in Fig. 1 for this purpose.

Referring to Fig. 1, it will be seen that the inner oil pipe or duct G extends throughout the length of said casting and substantially to the enlarged section of the chamber with in the adjustable cap C. At its inner end the pipe or duct G terminates in an internally threaded socket in which is screwed a plug that will be hereinafter more particularly described. The bore or passage with in the duct G is gradually reduced in diameter adjacent the plug socket to form a tapering seat with which co-operates a tapering plug valve N, the stem O of which extends to the outside of the burner and is connected with a hand wheel P by means of which it may be adjusted to control the feed of oil from the duct G as desired. The spraying or atomizing plug comprises two members M, M', the latter having a threaded section at the rear, that engages the thread in the oil supply pipe, and an expanded head Q, the outer forward surface of which is substantially parallel with the inner surface of the end of the cap C, whereby there is provided an annular passage R that communicates with the outlet or discharge opening E and with the interior of the body of the burner ca. ag. By adjusting the cap C it will be seen that the width of this passage R can be varied as may be found desirable.

While various forms of atomizing or spraying devices may be provided at the discharge end of the oil duct, it is preferred to use a form similar to that herein shown in which the outer member M' is provided with a central chamber S that communicates with the tubular passage in the inner plug member M through a plurality of lateral outlets or branch ducts T. The inner plug member as shown extends

somewhat beyond the threaded end of the member M' and has a central length of said extending passage adapted to conduct oil from the reservoir formed in the socket like portion of the pipe G to said chamber E. The ducts or oil discharge passages T extend tangentially from the tubular passage in the member M so that the oil passing therethrough under pressure is given a whirling or centrifugal motion within the casing. At its outer end the chamber S is provided with a suitable opening U that communicates with an outwardly flaring passage or depression in the forward face 15 of the plug which passage or depression V extends substantially to the burner outlet E. By such a construction the oil will be discharged into the burner outlet in the form of a body of very fine spray which will 20 be surrounded and mixed with the air passing through the burner casing and the passage R at the outer end thereof.

The gas conduit H is arranged about and is of less length than the oil duct and it is 25 provided at its end within the burner casing with a plurality of openings W, which, as shown in Fig. 1, are inclined so that the gas escaping therefrom is delivered into the body of air entering through the air inlet B 30 and in the direction in which the bodies of air and gas move toward the burner outlet E. The outlets W from the gas conduit are situated some distance in rear of the wider portion of the chamber within the burner 35 casing and the form of the cap G is such that the bodies of air and gas are caused to thoroughly mix while passing through such portion of the casing, whereby the mixture issuing from the passage R and burner outlet 40 E will be thoroughly commingled.

Having thus described the invention, what is claimed is:

1. The herein described oil and gas burner, comprising a casing having a discharge aperture or outlet at one end and an air inlet that opens through a side wall, a fitting extending into the casing and having two concentric ducts or passages formed therein and adapted to be respectively connected 45 with oil and gas supply pipes, the inner oil duct being of greater length than the gas duct and extending to a point adjacent the outlet from the casing, the gas duct having a plurality of discharge apertures in its end 50 within the casing, a hollow plug communicating with the end of the oil duct within the casing and adapted to cause oil received therein to be delivered to the outlet of the burner as a whirling spray, the end of the 55 casing in which said outlet is formed being adjustably connected with the body of the casing and forming about said plug an annular air passage connecting the interior of the casing with the outlet.

2. In a combined oil and gas burner, the combination of a casing having at one end an outlet for the combustible and a suitable air inlet in rear of said outlet, an oil duct extending longitudinally of the interior of the casing in alignment with said outlet, a 70 duct for gas surrounding a portion of the oil duct within the casing and provided with a plurality of apertures in its forward end, said duct and conduit both extending to the exterior of the casing and adapted to be connected with suitable supply pipes, and a spraying device connected with the discharge end of the oil duct and forming with the end of the casing through which the outlet extends an annular passage extending to said outlet.

3. In a combined oil and gas burner, the combination of a casing having openings in its end walls and an air inlet in one of its side walls, a cap adjustably connected with one end of said casing and forming an extension thereof which is of greater cross-sectional area than the body of the casing, said cap having a centrally arranged outlet in its side, an oil supply pipe extending through to the opening in the other end of the casing and into the interior of the cap, and a gas conduit of less length than the oil pipe surrounding said pipe and extending through the end wall of the casing, said conduit 95 having a plurality of apertures at its inner end within the casing.

4. In a combined oil and gas burner, the combination of a casing having a side wall, an air inlet in rear of said side wall, and a cap adjustably connected therewith, the cap having an air inlet opening in the side wall, and a cap 100 opening in the end of said cap, the cap being adjustably connected therewith, an oil inlet opening being provided in the side wall of said cap, a casting extending through an opening in the end of the casing opposite the air inlet, having two concentric ducts formed therein and adapted to be connected respectively to oil and gas supply pipes, the inner oil duct extending into the chamber within the casing and the gas duct being shorter and extending with apertures that communicate with the interior of the body of the casting, a hollow plug connected with 110 the inner oil duct within the casing and communicating with the oil duct, the free end of said plug being expanded and having a surface extending parallel with the inner surface of the adjustable cap about the outlet thereof.

5. In a hydrocarbon burner, the combination of a casing having a discharge aperture or outlet at one end, and a suitable air inlet, a supply pipe for conducting hydrocarbon into said casing, a mixing plug connected with the discharge end of said supply pipe and comprising two members, the outer plug

member having an interior chamber closed except for a suitable outlet, and the inner member communicating with the supply pipe and provided within said chamber with a plurality of lateral outlets, a cap surrounding the mixing plug and having an opening communicating with the outlet in said plug, said cap being adjustably mounted on the

casing, whereby it may be adjusted to and from the plug, for the purpose described. 19
In testimony whereof I affix my signature in presence of two witnesses.

ALFRED R. ANTHONY.
